CYLINDER DRYING UNIT FOR SLASHERS

Jack Hamrick, West Point, Ga., assignor to Batson-Cook Company, West Point Ga., a corporation of Georgia

Continuation of applications Ser. No. 50,063 and Ser. No. 50,076, Mar. 17, 1958. This application Aug. 1, 1961, Ser. No. 66,262

Term of patent 14 years

(Cl. D49—1)

FIG. 1

FIG. 2

FIG. 3

FIG.4

FIG.5

FIG.6

FIG. 1 is an elevational view showing one side of a cylinder drying unit for slashers showing my new design.

FIG. 2 is a top plan view of the cylinder drying unit shown in FIG. 1.

FIG. 3 is an end view of the cylinder drying unit shown in FIG. 1.

FIG. 4 is an elevational view showing one side of a cylinder drying unit showing another embodiment of my design.

FIG. 5 is a top plan view of the cylinder drying unit shown in FIG. 4.

FIG. 6 is an end view of the cylinder drying unit shown in FIG. 4.

In each embodiment, the side and end not shown are the same as the side and end shown. The broken lines in FIGS. 1, 2, 4 and 5 indicate intermediate length.

This application is a continuation of my copending applications Serial No. D. 50,063 and Serial No. D. 50,076, both filed March 17, 1958, now abandoned.

I claim:

The ornamental design for a cylinder drying unit for slashers, substantially as shown and described.
